UNITED STATES PATENT OFFICE.

ERSKINE RAMSAY, OF BIRMINGHAM, ALABAMA.

ROTARY DUMP.

Application filed October 31, 1921. Serial No. 511,655.

To all whom it may concern:

Be it known that I, ERSKINE RAMSAY, a citizen of the United States of America, residing at Birmingham, in the county of 5 Jefferson and State of Alabama, have invented certain new and useful Improvements in Rotary Dumps, of which the following is a specification.

My present invention relates to a rotary 10 dump adapted to rotate about its long axis and containing a track section onto which the car or cars to be dumped are run with the center of gravity of the car when loaded above the center of the dump.

15 More particularly the purpose of my invention is to devise an operating mechanism for rotating such a dump without the application of any power other than gravity as applied through the unbalanced condition 20 of the dump and by a weight detached from the dump but so connected thereto as to exert a force tending to start the dump's rotation towards dumping position, the weight being returned to initial position by 25 the inertia of the moving dump as it completes its dumping cycle.

A further object is to so design the mechanism that it will dump on one side only, or alternately on opposite sides, whichever 30 may be preferable, the latter being accomplished by complete rotations alternating as to directions of the former by partial rotations always in the same direction.

My invention in its simplest embodiment 35 will be best understood by reference to the accompanying drawings, in which:—

Fig. 1 is an end elevation of a rotary dump cage with the adjacent end trunnion ring omitted and the operating mechanism 40 adapted to give it complete rotations alternately in different directions.

Fig. 2 is a similar view of the dump after a complete rotation ready for a reverse rotation as to dump on the opposite side.

45 Fig. 3 is a similar view showing the manner of attachment of the cable when it is desired to dump on one side only by a half rotation always in the same direction.

Fig. 4 is a plan view of Fig. 1; and

50 Fig. 5 is a side elevation of Fig. 1.

Similar reference numerals refer to similar parts throughout the drawings.

As illustrated, the mine cars 1 approach the dump on mine track rails 2 which may be 55 level or have any desired slope, and I show

in Figs. 4 and 5, a train of cars passing through the dump and provided with swivel couplings 3 so that a car in the cage can be dumped without being uncoupled from the adjacent cars in the train. Any suitable 60 mechanism (not shown) may be provided for shifting the cars and bringing them into position one at a time or in successive groups of any desired number into the dump. The dump, which is conventionally illustrated, 65 comprises trunnion rings 4 suitably cross connected by side plates 5 and by a bottom plate 6. Each ring carries cross supports 7 upon which are mounted rails 8 of the track section in the dump which are disposed to 70 align with the track rails 2 when the dump is in initial or upright position. This track 8, as shown, is set so as to bring the axis of the car couplings 3 approximately in line with the dump's axis of rotation, but this 75 particular arrangement is of importance only where swivel or chain couplings are employed and it is desired to dump the car or cars in the dump without disconnecting it or them from the other cars in the 80 train or from the haulage means. The dump is provided on each side with suitable hold-down brackets 9 adapted to engage lugs 10 or any other desired part of the car or its 85 running gear so as to hold the car on the track 8 during the dumping operation.

All of the mechanism as thus far described is typical of any standard rotary dump construction and forms no essential part of my present invention, which is concerned with 90 the means for operating the dump without the use of power other than gravity. To this end I provide above the dump a pulley 11 mounted in any suitable support (not shown) and over this I pass a flexible rope, 95 chain or cable 12 which has one end passing about the dump and connected thereto in any suitable manner at the point 13 in the center of the dump bottom when standing in initial position. In other words, one end of 100 the cable substantially subtends one-half of the dump cage while the other end is connected to a weight 14, which in turn is connected by a rod or any suitable connection 105 15 to a screw eye 16 adjustably fastened in a suitable support 17. The dump has both trunnion rings provided with arcuate flanges which fit flush between the side and top plates 5 and 6 and form circular tracks 22 and 22^a. The cable passes about the track 110

22 and in a side plate 5 forming part of the track 22^a I form a notch 18 and a latch 19 is pressed by a spring 20 towards the dump to cause it to engage in this notch and both 5 stop and hold the dump in initial position. The trunnion rings 4 of the dump rest on roller supports which are typically illustrated by the flanged trunnion wheels 21. It will be observed that the weight suspension 10 elements 12 and 15 are stretched into substantial alignment between the screw eye 16 and the pulley 11 when the dump is in initial or car receiving position and that the pulley 11 is disposed to receive the cable 15 from or deliver it to the dump above its transverse center. Upon releasing the latch 19, the weight 14 is in position to exert its maximum pull upon the dump and will cause the latter to commence rotation to the 20 left, Fig. 1. As the weight 14 overcomes the inertia of the dump with the loaded car therein and the latter tilts, the dump itself becomes unbalanced to one side and commences to rotate with increasing rapidity 25 until, when the car in the dump has been inverted, the cage and car are moving at their highest speed and the weight 14 has fallen to the dotted line position, Fig. 1. After the car becomes inverted its center of 30 gravity changes and is again above the center of the dump so that as the momentum of the cage carries it past an angular travel of 180° the car again serves to unbalance the dump to one side and to co-operate with 35 the inertia of the dump to carry it through a complete rotation. In completing the last half of its rotation the dump's movement is opposed with increasing power by the weight 14 as the latter rises towards its full 40 line position and the weight and its cable connections are calculated to permit the dump to rotate only far enough to insure its being caught by the latch 19 and held in initial position. It is to be observed, 45 however, that when the dump has completed its rotation, the rope or cable 12 will then pass from the pulley 11 to the left about the dump (see Fig. 2) to which it is connected as before. When the latch is next released 50 the pull of the weight will turn the dump in clockwise direction and cause the car to discharge its contents to the right. As the operations succeed each other the cars are dumped alternately to right and left.

55 Under many conditions it is desired for the car to dump only on one side and then the cable 12 is shortened and connected to the dump track 22 at one side instead of at the dump bottom, the connection being made 60 at the side opposite from that towards which it is desired to dump. This is shown in Fig. 3 and here the dumping operation involves merely a half turn instead of a complete rotation. Here the center of gravity of the 65 upright loaded car and of the inverted

empty car must be above the center of the dump, but the vertical center line of the car does not need to align with the vertical center line of the dump as is desirable with dumps making a complete revolution, but 70 such center line can be displaced or tilted towards the dump's discharge side to unbalance the dump in such manner as to co-operate with the weight 14 in operating it. Such displaced car center lines are indicated 75 by the dotted lines A—A and B—B on Fig. 3, where C—C indicates the center line of the dump. Starting with the dump in its initial position shown in full lines in Fig. 3, the weight 14, either by itself or in co-operating with the overbalanced weight of the dump, will, upon the release of the latch, rotate the dump counter-clockwise and the weight 14 will drop to its lowest level when the dump has turned through an angle of 80 about 90°. As the dump continues to turn through the second angle of 90° its inertia is increasingly opposed by the weight and the car is brought gradually to rest by the action of the weight and its connections at 85 90 or near the completion of a half rotation, whereupon the weight 14 and, if desired, the now reversely unbalanced weight of the dump act to rotate the dump clockwise and the last 90° rotation of the dump again pulls 95 the weight 14 back up to initial position so that it brings the dump to rest in initial position wherein the latch 19 will engage in notch 18 and hold the dump until a new car is introduced. To dump continuously in a 100 reverse direction it is only necessary to shift the point of attachment of the cable to the opposite side of the dump. If desired, a notch 18 can be provided on both sides of the dump so that it can be latched with the 105 car inverted.

By the arrangement shown it will be obvious that I obtain not only a positive and rapid operation of the dump without the use of power means, such as steam, air or 110 electricity, but that the dump operating means also forms an effective break which functions with increasing power as the car approaches initial position or either extreme position to bring it easily to rest without undue shock or strain.

When it is desirable to control the speed of rotation of the dump, this may be done by a brake applied in any desired manner to the dump or to any element movable 120 therewith. A conventional brake mechanism is shown applied to the dump in Fig. 3. Here a lever 23 is used to operate a brake bar 24 pivoted at 25 to any suitable support (not shown) and carrying a brake 125 shoe 26 which by engagement with the track 22 will control the speed of the dump.

It is of course to be understood that the weight can be varied to produce the desired operation and the weight used may be of 130

any suitable character which is readily capable of variation to take care of different operating conditions.

My invention is not intended to be restricted in scope to the specific embodiments shown, but contemplates such modifications as come within the spirit and scope of the claims.

Having thus described my invention, 10 what I claim as new and desire to secure by Letters Patent, is:—

1. A rotary dump adapted to rotate about its long axis, means to support a car to be dumped in the dump in position to bring 15 its loaded center of gravity above the dump axis, a counter-weight suspended from a fixed support and having a flexible connection passed partway about the dump, a guide for said connection, and means to hold 20 the dump in initial position against the pull of said weight.

2. A rotary dump as described in claim 1, in which the connection is attached thereto at a point removed from the top center line 25 of the upright dump an arcuate distance of approximately half the angular travel of the dump in a given direction.

3. A rotary dump as described in claim 1, in which the dump is provided with an 30 arcuate track about which said connection winds and unwinds as the dump rotates.

4. The combination with a rotary dump and supports therefor, of a weight having a swinging support on one side, a guide located centrally above the dump, a flexible connection passing from the weight on the opposite side from and in line with said swinging support and leading over said guide and partway about the dump and connected at its end to the dump, and means 40 to hold the dump in initial position.

5. The combination with a rotary dump and its supports, of a counterweight having an overhead swinging support, a flexible connection attached to the counterweight, a pulley disposed substantially centrally above the dump, said flexible connection being passed over said pulley and partway 45 about the dump and attached to the latter, and latch means to hold the dump in initial 50 position against the action of said weight.

6. The combination with a rotary dump

and means to support it for rotation about a fixed axis, latch means to hold the dump in initial position with one edge disposed 55 substantially in a vertical plane with the dump axis, a counterweight, a flexible connection leading from the counterweight over the pulley and about an arc of the dump equal to half of its travel to dump a 60 car and there attached to the dump, and a fixed support having a swinging connection to the weight on the opposite side of said pulley from the edge thereof above referred to.

7. The combination with a rotary dump and means to support it for rotation about a fixed axis, a pulley disposed centrally above the dump, a counterweight, a flexible connection leading from the counterweight 70 over the pulley and partway about the dump and attached at its free end to the latter, a support having a swinging connection to the weight on the opposite side of said pulley, said swinging connection corresponding substantially in length to the length of the circumference of the dump segment about which said flexible connection is passed, and means to hold the dump in up-right position.

8. The combination with a rotary dump, of means to support it for rotation about a fixed axis, a pulley disposed above the dump with one side edge in a vertical plane with the dump axis, a counterweight, a flexible 85 connection from the counterweight passing over the pulley and leading from its said edge about an arc of the dump circumference equal to half the arc of rotation of the dump and having its free end connected to 90 the dump, an arcuate track on the dump for said connection to engage, means to hold the dump in initial position, a suitable support in the plane of rotation of said pulley, and a swinging connection therefrom to said 95 counterweight which corresponds in length substantially to the length of the flexible connection between the pulley and the point where such connection is attached to the dump.

In testimony whereof I affix my signature.
ERSKINE RAMSAY.
